CLAIM

The ornamental designs for a hose, as shown and described.

DESCRIPTION

FIG. 1 is a front perspective view of a hose showing my new design, the opposite side perspective view being identical thereto;

FIG. 2 is a plan view thereof;

FIG. 3 is an end view thereof, looking in the direction of the line 3—3 in FIG. 2, it being understood that the opposite end is a mirror image of that shown;

FIG. 4 is a front perspective view of a hose showing a second embodiment of my new design, the opposite side perspective view being identical thereto;

FIG. 5 is a plan view thereof, and,

FIG. 6 is an end view thereof, looking in the direction of the line 6—6 in FIG. 5, it being understood that the opposite end is a mirror image of that shown.

The broken line disclosure of the internal hose diameter is for illustrative purposes only and forms no part of the claimed design.
